FIG. 5.

UNITED STATES PATENT OFFICE.

WILLIAM E. WALKER AND GEORGE E. WILBUR, OF TAUNTON,
MASSACHUSETTS.

HEATING-STOVE.

SPECIFICATION forming part of Letters Patent No. 381,096, dated April 10, 1888.

Application filed April 2, 1885. Serial No. 161,017. (No model.)

To all whom it may concern:

Be it known that we, WILLIAM E. WALKER and GEORGE E. WILBUR, both of Taunton, in the county of Bristol and State of Massachusetts, citizens of the United States, have invented a new and useful Improvement in Heating-Stoves, of which the following is a full, clear, and exact description, reference being had to the accompanying drawings, forming a part of this specification, in explaining its nature, in which—

Figure 1 represents a vertical section, taken from side to side, of a heating-stove containing the features of our improvement. Fig. 2 represents a vertical section of the stove from front to rear. Fig. 3 is a plan view of the stove-top. Figs. 4 and 5 show details of the construction, which are hereinafter more particularly referred to.

20 The invention relates especially to an oven-cover made in two parts, one of which parts is pivoted to the top plate or rim surrounding the oven, to be swung horizontally, and the other of which is made entirely removable from said top plate or rim.

Referring to the drawings, A is the ash-pit; B, the fire-pot; C, the combustion-chamber; D, the outer casing of the main portion of the stove; D', the base-section of the stove.

30 E E are the down-flues connecting the combustion-chamber with the base-flue.

F is the uptake; G, the grate; H, the oven, which is located in the upper part of the stove, and like most ovens of this character it is cast with the top plate, h, of the stove.

The cover is made in two parts, one of which—the part H'—is attached to the top plate of the stove by the pivot h', so as to be swung or moved horizontally thereon from a position 40 over the oven to one side of the top plate, as represented in full and dotted lines in Fig. 3. This part comprises about two-thirds of the entire cover, and has a lateral extension, which forms a base for the support of the ornament h'. The other part, h³, of the oven-cover comprises about one-third of the entire cover, and is generally a fixture, but can be moved from the side when it is desired to expose another opening to the oven. It is held or secured in 50 place by means of the hook or projection h⁴,

(see Fig. 4,) which extends downwardly and outwardly from the narrow edge of this part of the cover, and which shuts into a hole, h⁶, in the top plate, h, (see Fig. 4,) in such a manner that the upper surface of the hook or projection bears against the under surface of the top plate. The part h³ of the cover also has the guides h⁷, which project downward from the inner surface of the cover below its lower edge, and are adapted when this part of the cover is in place to come in contact with the inner wall of the oven, and in connection with the hook or projection h⁴ to lock or hold the part securely in place. To remove this section h³ from the top plate, it is only necessary to tip it outward on the hook h⁴ sufficiently to permit the withdrawal of the hook from its hole. The swinging portion H' of the cover has a solid portion or part, h⁸, near the pivot h', which extends downward below the baseline h⁹ of the cover, to form the inclined surface h¹⁰ and the straight surface h¹¹. Upon the movement of the cover the incline rides upon the upper surface of the top plate, h, where it surrounds the oven-opening, and thereby 75 causes the entire cover to be somewhat lifted, so that its lower edge does not drag upon the upper surface of the top plate, h, and it is held thus lifted or lifted above the surface by the straight surface h¹¹, which continues to bear 80 upon the upper surface of the top plate, h, as the part H' is moved.

It will be observed that the part h³ of the cover is shaped to cover a comparatively small section of the oven; that it not only includes about one-third of the outer portion of the oven in circumference, but that its upper line is curved to correspond to this under or base line, which of course materially reduces the section of the oven-cover. A plan view of this 90 part is shown in Fig. 3. It will also be observed that the extension of the part H' of the cover, which supports the urn or other ornament, extends over the upper edge of the part h³ when it is closed.

The subject-matter of this application was removed by amendment, duly filed, from our application filed December 22, 1884, Serial No. 150,907.

It is to be understood that one of the essen-

tial features of the invention is to make the part h^3 of the oven entirely removable from the top plate of the stove in order that the opening to the oven may be entirely exposed when desired by the removal of one section of the cover and the swinging off of the other section, and that the means herein specified for holding this stationary section of the cover to the plate show only the conventional devices for such purposes, it being necessary to employ these or similar devices for holding the stationary section of the cover in place upon the top plate.

In an application of even date herewith, Serial No. 161,018, we have shown the subject-matter of this invention in connection with another feature—namely, a novel form of

grate—and we disclaim such matter as shown in this application as is common to and claimed in the other application.

20

Having thus fully described our invention, we claim and desire to secure by Letters Patent of the United States—

25

The combination of the oven H, the top plate, h , having the hole h^6 ; the stationary section h^3 of the oven-cover, having the hook h^4 , which enters the said hole h^6 , and the stays h^7 , and the swinging section H' , substantially as and for the purposes described.

WILLIAM E. WALKER.

GEO. E. WILBUR.
